UNITED STATES PATENT OFFICE.

JEROME B. SWEETLAND, OF PONTIAC, MICHIGAN.

FRUIT-EVAPORATOR.

SPECIFICATION forming part of Letters Patent No. 228,953, dated June 15, 1880.

Application filed January 3, 1880.

To all whom it may concern:

Be it known that I, JEROME B. SWEETLAND, of Pontiae, in the county of Oakland, and in the State of Michigan, have invented 5 certain new and useful Improvements in Fruit-Evaporators; and I do hereby declare that the following is a full, clear, and exact description thereof, reference being had to the accompanying drawings, and to the letters of 10 reference marked thereon, making a part of this specification.

The nature of my invention consists in the construction and arrangement of a fruit-evaporator in which are used both the direct radiated heat from a furnace and the radiated heat from one or more steam-boilers and one 15 or more steam-coils.

The evaporator is made in sections, so that it can be increased to any desired height according to the capacity desired. A partition is made in the base, which separates the one furnace from the steam-boilers with their furnaces, said partition extending high enough up to meet or connect with the end pieces of 25 the screen-frames, so that when said frames are put in a continuous wall will be formed across the evaporator from top to bottom, all as hereinafter more fully set forth.

In order to enable others skilled in the art 30 to which my invention appertains to make and use the same, I will now proceed to describe its construction and operation, referring to the annexed drawings, in which—

Figure 1 is a perspective view of my improved fruit-evaporator. Fig. 2 is a longitudinal vertical section of the same. Fig. 3 is a perspective view of the fruit-evaporator, showing two sections used together.

A represents the base of my fruit-evaporator, in which is a metal pan or jacket, B, containing at one end a cylindrical fire-box, C, extending across the same. In the pan or jacket B are also one, two, or more cylindrical boilers, D D, with interior fire-boxes, C' C', 45 extending across the same. All the fire-boxes are by pipes E connected with a common pipe, F, from which rises the smoke-stack G, so as to carry out the products of combustion from all the fire-boxes by one stack.

50 The body of the evaporator is intended to be made in sections, each section being com-

plete in itself, so that one, two, or more such sections may be used, according to the desired capacity of the evaporator.

The section of the body consists of a suitable frame, H, lined completely on the inside with sheet metal I, and provided at each end with a door, J.

On the two sides of the body H I are ledges a a, upon which are placed screens L L, of such size that their frames will come close together, as shown, one above the other. They are of such length that two or more of them will fit from end to end of the evaporator on the same ledges.

65 In the pan or jacket B is a partition, b, between the fire-box C and the first boiler D, and then extending upward in angular form, as shown, or otherwise, sufficiently high to unite with the adjacent end pieces of the bottom screens. When the screens are then put in, as represented in Fig. 2, a continuous partition is formed, dividing, as it were, the evaporator into two chambers.

60 In one chamber the fruit is acted upon by the direct radiated heat from the fire-box or furnace C, while in the other chamber it is acted upon by the milder heat from the boiler or boilers. This is of great importance in the successful drying of fruit, as when the fruit 70 is first put in it requires for the first five minutes or more a strong heat. By the insertion of another screen the first screen is moved back over the boiler, the second screen taking its place over the fire-box C, and so on in each 75 series.

At suitable intervals in each section of the body is placed a coil-pipe, M, which is connected with one of the boilers D—that is to say, each coil M should have a separate connection end with one of the boilers, so that the steam shall not pass from one coil to another. Each coil is placed in a position slightly inclined toward its connecting-pipe N, so that all condensation will pass back into the boiler. 80 However, each coil has an outlet, O, with stop-cock P, to blow off or allow part of the condensed water to pass into a tank, R.

85 By means of the coils M, I maintain a uniform steam-heat in the evaporator.

90 S is the roof of the evaporator, provided with the chimney V. This roof is removable,

so that it can be lifted off and another section put on, when the roof will be put on this section.

The object of subjecting the fruit first to the action of the strong heat is that thereby a sort of skin is formed rapidly on the fruit, thus in a measure sealing the same so as to retain the flavor of the fruit.

Having thus fully described my invention, what I claim as new, and desire to secure by Letters Patent, is—

1. The combination, in a fruit-drier, of a front compartment provided with a heating-furnace, a rear compartment provided with heating-boilers, one or more, and two series of trays, the frames of which at their point of junction form a continuation upwardly of the partition between the two heating-compartments, substantially as herein set forth.

2. In a fruit-drier, the combination of a base containing a front compartment having a heating-furnace, a rear compartment provided with one or more steam-boilers with furnaces, one or more sections, each containing two series of trays, the frames of which at their point of junction form a continuation upwardly of the division between the two heating-compartments, one or more steam-coils having separate connections with the boilers, and a roof or cover, substantially as and for the purposes herein set forth.

In testimony that I claim the foregoing I have hereunto set my hand this 3d day of January, 1880.

J. B. SWEETLAND.
